ACOUSTIC DEVICE SUPPORTER

Bess S. Liss, Detroit, Mich.

Application July 19, 1938, Serial No. 219,985

8 Claims. (Cl. 2—102)

This invention relates, in general, to improvements in garments and, in particular, to garments adapted for supporting in a concealed manner a part or parts of an apparatus, such as for aiding the hearing, which is to be carried on the person of the user to be so aided.

Persons who are afflicted with poor hearing are, for the most part, self-conscious thereof and find discomfort, not physical, but mental, when they attempt using hearing aids. Since this discomfort has been more mental than physical because of the necessity of having to expose the parts of the apparatus so used, it is proposed to provide some means whereby said parts can be concealed so as not to reveal the fact that they are being employed and also to enable the person so afflicted to employ said apparatus with comfort.

Therefore, the main object of this invention is to provide an improved type of garment to be worn by a person who has poor hearing and which is adapted for being worn, either as an inner or outer garment, so that the apparatus employed for aiding the hearing may be comfortably carried in a concealed manner.

Another object is to provide a garment with a continuous tunneled passageway whereby the cords of an electrical hearing-aid apparatus may be run in a concealed manner during use of said apparatus, said passageway having pockets for concealed disposal therein of the devices of said apparatus, and said tumbling and pockets being properly positioned so that said cords and devices may be carried with maximum comfort.

Another object herein is to provide means for ready attachment to an undergarment so that said undergarment is thereby made adaptable for carrying in a concealed and comfortable manner on the person of the wearer a complete hearing-aid apparatus, said undergarment being inexpensively convertible for the purpose outlined and without injuring the former appearance thereof.

Still another object is to provide an improved pocket-forming article in which is to be disposed a part of a hearing-aid apparatus and which article is adaptable for being carried on an inner or outer garment.

Other objects and advantages of the invention will become readily apparent from a reference to the following specification made in conjunction with the accompanying drawings of which there are three (3) sheets and in which:

Figure 1 is a view showing the novel garment in place on and in use by the wearer;

Fig. 2 is an enlarged detailed view, in elevation, of the garment shown in Fig. 1;

Fig. 3 is an enlarged view, in elevation, of a detail;

Figs. 4, 5 and 6 are detailed sections taken 5 through the lines 4—4, 5—5 and 6—6, respectively, in Fig. 2;

Fig. 7 is a view of a modification, showing the modified article in place on the wearer;

Figs. 8, 9 and 10 are enlarged front, side and 10 rear elevational views, respectively, of the article shown in Fig. 7, and

Fig. 11 is a section taken through the lines 11—11 in Fig. 10.

In Fig. 1 there is shown the bust of a woman 15 over which is disposed a brassière, generally indicated at 10, the showing of a brassière being purely illustrative and it being understood that the invention is equally applicable to other types of undergarments, such as corselettes, slips and 20 20 the like. The form and shape of the undergarment, such as shown at 10, are also illustrative, form and shape being optionally selective.

Brassière 10 is provided with shoulder straps 12 which are preferably widened along their 25 lengths for reasons to appear later. The free ends of straps 12 are inter-connectible in any desired manner at the back of brassière 10, for securing the latter about the wearer's bust, the opposite ends merging into the front main body 30 portion 14 of the brassière. The material or materials out of which the brassière 10 is made are purely selective. The brassière is provided with a lining, such as is shown at 16 in Figs. 4 and 5. The brassière may or may not be provided 35 with elastic webbing 18 for enabling proper fitting of the garment onto the wearer about the straps 12. And, the brassière proper may be reinforced in any suitable manner to increase its life and maintain its original shape and assembly. 40

To the inner surface of the shoulder strap 12 which is preferably on the side of brassière 10 corresponding to that side of the head on which the affected ear is located, there is marginally stitched or otherwise secured an elongated strip 45 portion 19 of the lining 16, lining 16 being of any selected material, said strip portion 19 extending along the under face of said strap 12 substantially from its free end and corresponding substantially in width and contour to said strap to 50 provide with said strap thereat an elongated pocket or tunnel 22 (see Fig. 6). Strip portion 19 along its length is provided with a plurality of spaced openings 24 disposed transversely therefor of for affording a series of accesses to the strap 55

socket 22. In a majority of cases it is desirable to have the strip portion 19 and pocket 22 extend substantially the entire length of the strap 12 as shown, but this length is obviously alterable 5 at will and as desired, the provision of the pocket or tunnel 22 in a concealed manner under the outer facing of the strap 12 being paramount. The width of said strip portion 19 is optional but must obviously be great enough for the purpose to be explained later. Each strap 12 may be provided with a pocket 22, if desired, but this is normally not necessary for obvious reasons.

In the front of each of the straps 12 adjacent the shoulder portion thereof there is provided 15 an opening 26 which communicates with the pocket 22, and each of said openings, if the brassière 10 is made of any material other than lace or other open-work fabric, is covered with a section of netted material 28 stitched or otherwise secured to the strap 12 over the opening 26 to perform a function to be later explained. The shape of the opening 26 is optional, but it preferably extends to within a comparatively short distance, say one or two inches, from the shoulder 20 level. Also, though only one opening 26 is needed for practical purposes, two are preferably provided, one on each strap 12, for the sake of symmetry and appearance.

To the inner surface of body portion 14 of 30 brassière 10 directly below the strap 12 is secured a section of fabric 30 to form with said body portion thereat an inner pocket 32, pocket 32 being formed by marginal stitching 34 and being free of said stitching at the top to form an opening 36 for providing communication between the strap pocket 22 and the pocket 32. Pocket 32 is preferably disposed as a whole above the actual bust area of the brassière and in communication with the netted opening 26, the width 35 of opening 36 thereinto being preferably variable by means of elastic webbing 38 which extends between and is secured to loose portions of section 30 directly below said opening. After the device to be carried by pocket 32 has been inserted thereinto and its most comfortable position determined, the wearer may add stitching across the bottom of the pocket 32 for supporting said device at the determined and proper level, the webbing 38 preventing sidewise displacement of the device after said positioning.

The bottom of pocket 32 lies substantially above the actual bust portion of the brassière and has an opening 40 therein. The fabric section 30 materially decreases in width beyond the opening 40 and continues downwardly, as at 41, to provide in conjunction with the portion of the brassière 10 thereat a narrow, elongated, open-ended pocket or tunnel 42, pocket 42 being formed by the customary method of stitching or otherwise securing the two side edges of the reduced portion 41 of fabric 30 below opening 40 to the brassière 10.

An additional section of fabric 44 is provided and stitched or otherwise secured at its two 65 side edges and bottom to the inner surface of brassière 10 directly below the tunnel 42 to form with the brassière thereat an enlarged, concealed pocket 46 in communication with said tunnel. Pocket 46 is disposed substantially wholly on the side of brassière 10 embodying the aforementioned tunnels and pockets and extends for a substantial distance toward the corresponding free end of the brassière to provide for the adjustment of the position of the device to be carried by the pocket 46. The opening into the

75 pocket 46 from the tunnel 42 may be provided with means, such as elastic webbing 48, for resilient adjustment of the size thereof.

As shown in Fig. 1, the receiver 50 of the hearing-aid arrangement is fitted into the afflicted ear and an electric cord 52 extends therefrom preferably through a pin 54 which is concealed in the hair. The cord 52 leads downwardly in any desired manner selectively into and through any one of the spaced openings 24 in the strip portion 19 of the lining 16 to run therefrom along the tunneled pocket 22 in the brassière strap 12 into proximity with the opening 36. To the free end of cord 52 is electrically secured a microphone 56 which is placed through the flexible opening 36 into the pocket 32 and arranged therein in the position which will afford the greatest comfort, any of such positions affording outside communication of sound waves with the microphone through the netted opening 26, after which positioning the pocket 32 may be stitched near the bottom of the microphone to hold same at the level of the selected position, the elastic webbing 38 tending to bind the microphone in place within the pocket 32. For associating the receiver 50 and microphone 56 with a source of power, a second cord 58 is electrically secured at one end to the microphone 56 and at the opposite end to a battery 60, the cord 58 passing between said microphone and battery from the pocket 32 through the opening 40, thence through the tunneled pocket 42, and finally into the pocket 46 wherein the battery 60 is confined, pocket 46 being large enough to accommodate the battery in any of a number of selected positions. It is seen, therefore, that the system of tunnels and pockets forms a continuous run for the parts of the hearing-aid apparatus, that said parts are concealed thereby so as to make same substantially exteriorly unnoticeable, and that said parts are supported in the most available and comfortable positions.

In Figs. 7 through 11, there is shown a pocket-forming casing, generally indicated at 62, which is adapted for being interiorly or exteriorly supported by a man's belt 64, as shown in Fig. 7, or which is likewise suitable for being supported by the previously described brassière 10 underneath an outer garment or in, say, the pocket 46. Casing 62 is made preferably of some type 50 of wear-resisting fabric, or it might be made of leather or the like, and is proportioned in size in accordance with the device to be contained therein, said device being presumably a battery, or a microphone, or a combination battery-microphone.

Casing 62 is provided with a false bottom 66 to prevent wear and frayed edges thereat, a substantially inflexible fabric strip 68 of double thickness providing the only means for supporting the battery or microphone within the casing from beneath and preventing its displacement through bottom 66, said strip encircling said casing at its bottom 66, its front 70 and its back 72 and extending centrally of said bottom, front and back. To the upper end of strip 68 at rear 72 of casing 62 is secured an end of a flexible strap 74, strap 74 being adapted for encircling the top of casing 62 and to have its free end removably attached in any suitable 70 manner near the top of casing front 70, such as by a button—button hole arrangement 76, as shown, for securely and resiliently holding the device within the casing in place.

If it is desired to use casing 62 in conjunction 75

with a battery-microphone combination, then it is advisable to provide, in front 70 of the casing at a point near which the microphone portion of said combination is to be supported, an opening 78. Except for the opening 78, which may or may not be provided with a section of perforated material, front 70 of the casing is preferably imperforate, presenting an attractive, unbroken appearance.

10 Sides 80 of casing 62 may either be formed by overlapping portions of front 70 or furnished separately, as desired, but the former is preferable. Sides 80 at the rear are preferably folded inwardly toward the strip 68 to form opposite portions 82 of the back 72, the adjacent side edges of portions 82 being spaced from the opposite edges of strip 68 and having stitched or otherwise secured thereon a pair of reenforcing strips 84. A plurality of spaced, flexible bands 86 of 20 double thickness are provided transversely of and at the rear of the casing 62, the ends of said bands being stitched or otherwise secured to and between the reenforcing strips 84 and back portions 82, as shown in Fig. 10, so that the 25 space within casing 62 is adjustable for accommodating variable sizes of hearing-aid devices. Casing 62 is provided at its rear 72 and in any appropriate manner with means, such as spaced pins 88, for interiorly or exteriorly securing 30 said casing to a garment, said casing being also and selectively supportable, if desired, by the belt 64 which may be fed, as shown in Fig. 10, between a pair of the spaced bands 86 and behind the strip 68 thereat. The casing 62 is provided with a flap 90 which is stitched to the back 72 and is adapted for enclosing the top of the casing and to be held in place by the strap 74 which overlies it.

Although the invention has been described with 40 some detail such description is not intended to be definitive of the limits of the inventive idea. The right is reserved to make such changes in the arrangement of parts, in the specification and in the drawings as will come within the pur- 45 view of the attached claims.

What I claim is:

1. In a garment, a tunneled passageway formed along the inner surface of the garment, and a pocket formed on said inner surface in communication with said passageway, said passageway being adapted for receiving the conduits of an electrical hearing-aid apparatus and said pocket being adapted for receiving the microphone of said apparatus, whereby said conduits and 55 microphone are supported and concealed by said passageway and pocket.

2. In a garment, a tunneled passageway formed along the inner surface of the garment, a pocket formed on said inner surface in communication 60 with said passageway, and an opening in the outer surface of the garment opposite said pocket, said passageway being adapted for receiving the conduits of an electrical hearing-aid apparatus and said pocket being adapted for receiving the microphone of said apparatus and communicating same with said opening, whereby 65 said conduits and microphone are supported and concealed by said passageway and pocket.

3. In a garment, a tunneled passageway formed 70 along the inner surface of the garment, and a pair of pockets formed on said inner surface in

communication with said passageway, said passageway being adapted for receiving the conduits of an electrical hearing-aid apparatus and thereby concealing same, the conduits being operatively connected to the microphone and battery of the apparatus and said pockets being adapted for receiving and concealing same. 5

4. In a garment having a body portion and a shoulder strap portion, a tunneled passageway formed in and along the shoulder strap portion 10 and adapted for receiving and concealing the conduits of an electrical hearing-aid apparatus, and a pocket formed on the inner surface of the body portion in communication with said passageway and adapted for receiving and concealing the microphone of said apparatus which is operatively connected to said conduits. 15

5. In a garment having a body portion and a shoulder strap portion, a tunneled passageway formed in and along the shoulder strap portion 20 and continuing therefrom along the inner surface of the body portion and adapted for receiving and concealing the conduits of an electrical hearing-aid apparatus, and a pocket formed on the inner surface of the body portion in communication with said passageway and adapted 25 for receiving and concealing the battery of said apparatus which is operatively connected to said conduits.

6. In a garment having a body portion and a shoulder strap portion, a tunneled passageway formed in and along the shoulder strap portion and continuing therefrom along the inner surface of the body portion and adapted for receiving and concealing the conduits of an electrical hearing-aid apparatus, and a pair of pockets 30 formed on the inner surface of the body portion in communication with said passageway and adapted for receiving and concealing the microphone and battery of said apparatus which are 35 operatively connected to said conduits. 40

7. In a garment having a body portion and a shoulder strap portion, a tunneled passageway formed in and along the shoulder strap portion and adapted for receiving and concealing the conduits of an electrical hearing-aid apparatus, a pocket formed on the inner surface of the body portion in communication with said passageway and adapted for receiving and concealing the microphone of said apparatus which is operatively connected to said conduits, and an opening 45 in the outer surface of the body portion adjacent said pocket and microphone facing said opening. 50

8. An inner garment for supporting the parts of an electrical system employed for aiding the hearing of an individual comprising, a tunneled passageway formed along the inner surface of the garment, and a pair of pockets formed on said inner surface and in communication with said passageway, one of said pockets being disposed intermediate the ends of said passageway and the other of said pockets being disposed at one of said ends, said pockets and said passageway being adapted for receiving the microphone, battery and connecting conduits of the 60 system for supporting and concealing same, the battery and microphone being operatively connected to and by the conduits. 65
